SPRING DOOR HINGE AND CHECK

Murray W. Henry, San Antonio, Tex.

Application November 30, 1939, Serial No. 306,980

6 Claims. (Cl. 16—50)

My invention relates to improvements in spring door hinges and checks and its general object is to provide a device of this character in which the operating mechanism is concealed within the hinge and which provides for uniform speed of closure.

A further object of my invention is to provide a device of this character in which a braking effect is obtained when the door is opened and again when the door is being closed.

A still further object of my invention is to provide a device of this character, which is neat in appearance, compact, which may be manufactured quite economically, and which may be readily installed.

A still further object of my invention is to provide a device of this character whereby the speed of the door closure may be readily adjusted from the exterior of the unit without disassembling.

With these and other objects in view, as will hereinafter more fully appear and which will be more particularly pointed out in the appended claims, reference is now made to the accompanying drawings forming a part of this application, in which:

Fig. 1 is a front elevational view of my improved spring door hinge and check;

Fig. 2 is a central, vertical, longitudinal section view, with door in closed position;

Fig. 3 is a view similar to Fig. 2 with the door partially opened;

Fig. 4 is a horizontal section view, taken on the line 4—4 of Fig. 1, looking in the direction of the arrows;

Fig. 5 is a horizontal section view, taken on the line 5—5 of Fig. 2, looking in the direction of the arrows;

Fig. 6 is a horizontal section view, taken on the line 6—6 of Fig. 2, looking in the direction of the arrows;

Fig. 7 is a horizontal section view, taken on the line 7—7 of Fig. 2, looking in the direction of the arrows;

Fig. 8 is a detailed view, partly broken away, showing the piston;

Fig. 9 is a detailed view, showing one of the metal discs;

Fig. 10 is also a detailed view, showing another one of the metal discs; and

Fig. 11 is a detailed view, showing one of the composition or fibre discs.

Referring now to the drawings in which similar reference characters represent similar parts, my invention comprises conventional left and

right hinge leaves, 10 and 12, provided with the usual circular holes, through which nails or screws may be inserted to fasten the leaves to the door and casing respectively.

While I have shown the leaf 10 as being the moving leaf, it will be understood that either, or both, of the leaves may move. Left leaf 10 is provided with integrally formed cylindrical casings, 14 and 16, while right leaf 12 is provided with similar casings 18 and 20. These casings 10 interlock to form, with upper end portion 22 and lower end portion 24, the hollow, cylindrical hinge or casing which contains the spring and checking mechanism.

Referring now more particularly to Figs. 2 and 3, a slotted, threaded bolt is shown at 26, one end of a spiral spring 28 engaging the slot in the bolt, the other end of the spiral spring being affixed to arm 30, of upper end portion 22. The lower end of the slotted bolt is adapted to contact a metal cap 32, the bottom portion of which contacts the upper surface of the top metal disc 34, three of the discs 34 being shown, although any desired number may be used. Between these metal discs 34 are composition or fibre discs 36 and metal discs 38, the metal and composition or fibre discs being alternately disposed. All the discs are adapted to fit over the top or square end of piston 40.

The lower end of piston 40 is round and interposed between the cylinder 42, which is slidably mounted around the lower end of piston 40, and the bottom side of lower metal disc 34 is a coil spring 46.

The extreme lower end of piston 40 terminates in a ratchet wheel 48, adapted to be engaged by pawl 50 which is pressed inwardly and held in engagement with the ratchet wheel under action of spring 52. Upper end portion 22 and lower end portion 24 are secured to the inside casing 54 by means of pins 56. The inside casing 54, or pintle proper, is provided with grooves 58, for a distance adjacent either end, as shown in Figs. 2 and 3. These grooves 58 are adapted to receive the lugs of the cylinder 42 and metal discs 34. The top portion of the inside casing 54 is held in position by means of pins 60 and an adjustable floating ring 62 is provided with a plurality of threaded openings 64, adapted to receive threaded bolt 66, for the purpose of adjusting the tension of the outside or main coil spring 65, the top end of which is affixed to the floating ring 62. The bottom end of the main coil spring 65 is affixed to the lower end of the inside casing 54. The lower end of the inside casing 54 is affixed to the

outside cylindrical casing by means of pins 68. The cylinder 42 is provided with a spiral cam groove 70. Affixed to the outside casing is a pin 72 which slides in cam groove 70, forcing the cylinder 42 upward as the door is opened, the cylinder being prevented from turning due to its lugs being slidably mounted in grooves 58 of the inside casing.

In operation, as the door is opened the cylinder 10 is forced upward under action of the pin 72, operating in the cam groove 70 of the cylinder. This compresses coil spring 46 against the series 15 of discs and the cylinder. The composition discs 36, being interposed between the metal discs 34 and 36, creates a noiseless braking effect which is gradually increased until the opening movement of the door is stopped. During this opening movement, the piston turns and the pawl 50 rides over the ratchets of wheel 48. The door 20 then starts to close under the action of coil spring 65, and the pawl 50 engages ratchet wheel 48, turning the piston. The openings in metal discs 34, being round, allows the piston to turn through these openings. The discs 34 are held against 25 turning by reason of the lugs of the discs being in position in the grooves 58 of the inside casing. The metal discs 38, having square openings to fit the piston, turn as the piston turns, and the composition discs 36, having round openings, do 30 not turn with the piston and thus a noiseless braking effect is obtained. The cylinder returns to normal position as the door closes under action of spring 46 and pin 72 operating in cam groove 70 of the cylinder.

35 When the hinge is assembled, spiral spring 28 is wound tightly, and the constant pressure exerted by this spring on the slotted bolt 26 keeps the bolt in contact with the metal cap 32. It will be apparent, therefore, that any shrinkage 40 in the discs, due to wear, or other causes, will be automatically taken up by the slotted bolt under action of the spiral spring.

The composition or fibre discs may be made of such material as synthetic rubber, any well known fibre composition, Bakelite, asbestos compound, etc., and any desired number of these discs may be used, as well as any desired number of the metal discs.

It will be understood that my improved spring 50 door hinge and check may be used as a plain, butt, or semi-butt hinge, and that small openings, if desired, may be formed in the casing, for the purpose of oiling the mechanism without the necessity of disassembling the hinge.

55 While I have illustrated and described the invention in some detail, it is to be understood that

the invention is not to be limited to such details, but only by the spirit of the invention and the scope of the appended claims.

I claim:

1. A spring door hinge and check of the character described, comprising left and right hinge leaves with interlocking, integrally formed casting portions, spring means for braking the door as it opens, and spring means for closing the door automatically at a uniform rate of speed. 10

2. A spring door hinge and check of the character described, comprising left and right hinge leaves with interlocking, integrally formed casting portions, adjustable spring means for braking the door as it opens, and adjustable spring 15 means for closing the door automatically at a uniform rate of speed.

3. A spring door hinge and check of the character described, comprising left and right hinge leaves with interlocking, integrally formed casting portions, adjustable spring means for braking the door to a stop as it opens, and exterior 20 adjustable spring means for closing the door automatically at a uniform rate of speed.

4. A spring door hinge and check of the character described, comprising left and right hinge leaves with interlocking, integrally formed casting portions, means for braking the door as it opens, said means comprising a series of alternately disposed metal and composition discs, one 30 series of the metal discs being adapted to rotate under pressure against the non-rotating composition discs, and means for closing the door automatically at a uniform rate of speed. 25

5. A spring door hinge and check of the character described, comprising left and right hinge leaves with interlocking, integrally formed casting portions, means for braking the door as it opens, said means comprising a series of alternately disposed metal and composition discs, said 40 disc series and the individual discs thereof being maintained at a constant pressure when the door is closed by means of a slotted bolt and spiral spring.

6. A spring door hinge and check of the character described, comprising left and right hinge leaves with interlocking, integrally formed casting portions, a plurality of alternately disposed metal and fibre discs normally maintained under constant spring pressure, spring means for 50 exerting pressure on said discs as door is being opened, to obtain a braking effect and spring means for closing the door at a uniform rate of speed. 45
